Primary Examiner — Lilyana Bekic(74) *Attorney, Agent, or Firm* — Collard & Roe, P.C.(57) **CLAIM**

The ornamental design for an inhaler, as shown and described.

DESCRIPTION

FIG. 1 is a left side view of an inhaler, showing my new design;

FIG. 2 is a rear view thereof;

FIG. 3 is a right side view thereof;

FIG. 4 is a front view thereof;

FIG. 5 is a top view thereof;

FIG. 6 is a bottom view thereof; and,

FIG. 7 is a top, rear and left side perspective view thereof.

The area shown in broken lines in FIG. 6 depicts a portion of the inhaler that forms no part of the claimed design.
